UNITED STATES PATENT OFFICE.

CHARLES N. TUCKER, OF PAWTUCKET, RHODE ISLAND, ASSIGNOR OF ONE-THIRD TO
JAMES A. TUCKER, OF WALPOLE, MASSACHUSETTS, AND ONE-THIRD TO EVERETT E.
SALISBURY, OF PROVIDENCE, RHODE ISLAND.

PICKER-CHECK.

1,013,835.

Specification of Letters Patent.

Patented Jan. 2, 1912.

Application filed March 4, 1911. Serial No. 612,265.

To all whom it may concern:

Be it known that I, CHARLES N. TUCKER, a citizen of the United States, residing at Pawtucket, in the county of Providence and State of Rhode Island, have invented certain new and useful Improvements in Picker-Checks, of which the following is a specification, reference being had to the accompanying drawings.

This invention relates to improvements in picker checks for looms, for checking the motion of the picker staff at the extremities of its throw, the object of the invention being to provide a simple and efficient device of this character, which may be adjusted so as to vary the extent of its checking action on the picker staff, another object being to enable the heel strap to be materially shortened so as to effect an economy in the construction of the picker check and in the cost of maintaining the loom, another object being to provide an improved device which prevents the heel strap from slipping from and becoming disconnected from the lower end of the picker staff.

Another object of the invention is to provide an improved device to prevent the picker staff from jumping up and becoming unseated from the shoe if the heel strap should break.

With the above and other objects in view, my invention consists in the construction, combination and arrangement of devices hereinafter described and claimed.

In the accompanying drawings—Figure 1 is an elevation of a picker staff provided with my improved check and showing the same in connection with the coacting parts of a loom. Fig. 2 is a vertical sectional view on the plane indicated by the line *a—a* of Fig. 1. Fig. 3 is a horizontal sectional view on the plane indicated by the line *b—b* of Fig. 1. Fig. 4 is a similar view on the plane indicated by the line *c—c* of Fig. 1. Fig. 5 is a detail transverse sectional view taken on the plane indicated by the line *d—d* of Fig. 1.

The picker staff 1, swings upon the step 2, and operates in the lay 3. The rocking foot 4 of the staff has a vertical slot 5, which receives a lug 6 that projects from the upper side of the step. An ear 7 depends from one side of the step and is provided with a horizontally disposed spindle 8 which extends

transversely under the step and on which is mounted the roller 9 which is turned in one direction by a spring 10. All of these parts are of the usual construction.

One end of the heel strap 11 is attached to the roller 9. In accordance with my invention, the opposite end of the heel strap instead of being attached directly to the lower end of the picker staff as has heretofore usually been done, is attached as by means of a suitable belt hook to a transverse hook 12 at the lower end of a hook rod 13. The hook 12 extends under the step. The upper end of the rod has a laterally extending portion 14 which has a U-shaped upwardly extending arm 15 which bears against the inner side of the picker staff and is secured thereto by means of a bolt 16 and a clip shaped washer 17, the said bolt extending through the washer, operating in the slot formed by the arm 15 and being engaged by a nut 18 which bears on the outer side of the washer and coacts with the washer to clamp the arm 15 between the washer and the picker staff and to enable the said arm to be adjusted vertically so as to correspondingly adjust the said hook rod 13. The major portion of the hook rod extends downwardly on one side of the picker staff, and also on one side of the foot 2, and the step.

A clip 19 is secured on the outer side of the picker staff, the bolt and also the upwardly extending portion of the foot. A washer 21 on the said bolt is interposed between the picker staff and the clip. The clip 19 has an outwardly extending arm or wing 22, which extends behind the hook rod 13. The picker staff is slidable to some extent in the usual opening 23, in the step 2. By first loosening the nut 18, on the bolt 16, the rod 13 may be raised or lowered on the picker staff so as to vary the tension on the spring 10 as may be required according to the desired check on the picker staff. To increase the check, the rod 13 is raised. To take off or loosen the check, the said rod is lowered. Having adjusted the rod 13 as required, the nut 18 is then tightened on the bolt 16, so as to cause the washer 17 to firmly grip the slotted arm 15 of the rod, and secure the said arm, and hence the rod in the required adjusted position on the picker staff.

Since the rod 13 to which the heel strap is

connected is disposed on the inner side of the picker staff, the heel strap is very much shorter than has heretofore been required, and enables a considerable economy to be effected. Moreover, should the heel strap break, another can be readily substituted in its stead, and connected to the hook arm of the rod 13, and without the necessity of removing any bolt or other like devices, and without the necessity of detaching the picker staff from the rocking foot, as the heel strap in accordance with my invention, instead of being connected to the outside of the picker staff by the bolt 20, is connected to the hook arm 12 of the rod 13. Furthermore, by connecting the heel strap to the hook arm 12, the heel strap is effectually prevented from slipping from the picker staff, the clip 19 with its wing 22 forms a guide for the hook rod 13, is not subject to wear, and will last indefinitely. Moreover my improved devices cause the picker staff to throw the shuttle straighter than heretofore, prevent the picker staff from getting out of position and from getting out of order.

I claim:

1. In mechanism of the class described, the combination of a step, a picker staff mounted thereon, a spring actuated roller, and a rod attached to the staff, and having an arm extending transversely under the step, and a heel strap attached to the roller and also attached to said arm.

2. A picker staff having an adjustable rod on one side thereof, and provided with an arm to extend transversely under the step, and serve for the attachment of a heel strap.

3. A picker staff having an adjustable rod

on one side thereof, and provided with an arm to extend transversely under the step, and serve for the attachment of a heel strap, said arm of the rod forming a hook to prevent the picker staff from becoming unseated on the step in the event of the breaking of the heel strap.

4. A picker staff having a hook rod provided at its lower end with an arm to extend transversely under a step, and provided at its upper end with an off-set vertically slotted arm to bear against one side of the staff, in combination with a bolt extending through the staff and the slot of said arm, a clip on said bolt and bearings against said arm, and a nut on the bolt and bearing against the outer side of the clip.

5. A picker staff having a hook rod provided at its lower end with an arm to extend transversely under a step, and provided at its upper end with an off-set vertically slotted arm to bear against one side of the staff, in combination with a bolt extending through the staff and the slot of said arm, a clip on said bolt and bearing against said arm, and a nut on the bolt bearing against the outer side of the clip, the staff being further provided with a guide clip attached thereto and provided with an outstanding wing disposed at one side of the said rod.

In testimony whereof I hereunto affix my signature in the presence of two witnesses.

CHARLES N. TUCKER.
